Inventor:
George Duisenberg

UNITED STATES PATENT OFFICE

GEORG DUISENBERG, OF BREMEN, GERMANY

ROLLER SKATE

Application filed June 2, 1928, Serial No. 282,439, and in Germany April 13, 1928.

The object of the present invention is to produce a roller skate which is particularly suitable for figure skating, and the invention consists in providing the skate with a ground roller situated in a substantially central position under the arch of the foot. Preferably the skate is also provided with auxiliary rollers mounted at the ends of the foot plate in alignment with the ground roller and carried in an elevated position relative to the latter, the auxiliary rollers being adapted to swivel like castors so as to adjust themselves to the different curvatures in which the skate is running.

15 Fig. 1 of the accompanying drawings represents a side view of the improved skate, Fig. 2, a top view of the same,

Fig. 3, a top view showing a modified arrangement of the auxiliary rollers,

20 Fig. 4, a side view showing a modification of the main ground roller mount,

Fig. 5, a top view of Fig. 4,

Fig. 6, a section on the line VI—VI of Fig. 4, and

25 Fig. 7 is a top view of a skate combining the features of claims 3 and 4.

The roller skate is provided with the usual foot plate *a* and is fitted with a ground roller *b* arranged substantially in a central position so as to be situated under the arch of the foot.

In addition to the main ground roller, the skate is preferably provided with auxiliary rollers *c* and *d* arranged in alignment with the roller *b*, one at the front and the other at the rear end of the skate. The auxiliary rollers are on a higher level than the roller *b* and do not normally touch the ground. They are preferably of smaller diameter than the roller *b* and mounted like castors so that they can adjust themselves to the curvature in which the skate is running.

40 Fig. 1 shows such an arrangement, the rollers *c* and *d* being mounted in swivelled forks *e* with the roller centres outside the vertical axes of the swivel pins *f*.

A modified arrangement is shown in Fig. 3 wherein the roller is mounted loosely on a spherical hub *h* which in its turn is mounted by means of a shaft *g* in the fork *e*, the roller

being adapted to turn about the hub and to be deflected thereon to follow the curvature of the path. To enable the roller to be mounted on the hub it is provided with a detachable center portion *i* extended through half the thickness of the roller.

The main ground roller *b* may, as shown in Fig. 1, be held between permanently fixed supporting arms. As an alternative, a bearing bracket *l* (Figs. 4 and 5) may be used, the position of which can be adjusted according to requirements. The foot plate *a* is formed with a longitudinally elongated aperture *n*, and the bracket *l* is formed with lips *o* adapted to engage the plate edges within the aperture so as to connect the bracket to the plate and allow it to slide thereon. A plate extension *m* on the bracket *l* is formed with an elongated slot *r* for the reception of a fastening screw *p* secured to the foot plate *a*. A wing-nut *q* on the screw is used for fastening the plate *m* and thus the roller bracket *l* in adjusted position. Additional screws or other fastening members may be resorted to.

The roller is mounted by means of a ball bearing on an axle *k* and projects through the aperture *n* so as to carry the foot plate in as low a position as possible.

The connection of the skate to the footwear is effected in any suitable known manner.

I claim:

1. A roller skate comprising a foot plate having a centrally disposed longitudinally elongated aperture, a bearing bracket having lips engaging the plate edges within said aperture so as to connect the bracket to the plate and allow its position thereon to be adjusted longitudinally, means for securing the bracket to the plate in adjusted position, a ground roller mounted in said bracket, and castors mounted at the ends of the plate in an elevated position relative to said roller.

2. A roller skate as claimed in claim 1 wherein the means for securing the bracket in adjusted position comprises a screw and a wing nut.

3. A roller skate having three rollers arranged in the same vertical plane, the end rollers being on a higher level than the mid-

dle roller, the end rollers being deflectable and adapted to adjust themselves automatically to the travelling direction.

4. A roller skate having three rollers arranged in the same vertical plane, the end rollers being on a higher level than the middle roller, and spherical hubs whereon the end rollers are mounted so as to allow of being deflected in a horizontal plane.

GEORG DUISENBERG.
